UNITED STATES PATENT OFFICE.

CHARLES E. COE, OF LEESBURG, KANSAS, ASSIGNOR, BY DIRECT AND MESNE ASSIGNMENTS, OF TWO-THIRDS TO LEONARD G. FATH, AMOS SAWYER, AND EDWARD L. WAGGONER, ALL OF HILLSBOROUGH, ILLINOIS.

SCREW-THREADING MACHINE.

SPECIFICATION forming part of Letters Patent No. 317,303, dated May 5, 1885.

Application filed January 20, 1885. (No model.)

To all whom it may concern:

Be it known that I, CHARLES E. COE, a citizen of the United States, residing at Leesburg, in the county of Stafford and State of Kansas, have invented certain new and useful Improvements in Screw-Threading Machines, of which the following is a description.

This invention relates to that class of devices which are intended to turn and square up shoulders and to cut new screw-threads by hand to supply the place of old screw-threads which have become worn in use, and its object is particularly to form new screw-ends on carriage-axles and to extend the screw-thread farther onto pipes, bolts, &c.

To this end my invention consists in the construction and combination of parts forming a machine for turning metals and cutting screw-threads thereon by hand, hereinafter described and claimed, reference being had to the accompanying drawings, in which—

Figure 1 is a side elevation of my invention, partly broken away to show the inner parts. Fig. 2 is a front end view of the same. Fig. 3 is a view of the same end with the front plate removed, and Fig. 4 is a central longitudinal vertical section of the invention in full.

A represents a hollow sleeve of sufficient internal diameter to receive any axle, C, or pipe which it is to act upon.

B represents a series of screws entering the sleeve radially at each end thereof, by means of which the sleeve is trued into line with the axle C or other work, and then bound tightly thereon. The exterior of the sleeve is turned cylindrical, and the forward end thereof is provided with a flange, D, which is cut away at three places to admit three of the adjusting-screws B.

E is a ring fitted neatly to turn upon the sleeve, and provided with arms F, extending forward over the flange D, to serve as securing-points to the front plate, G, which is se-

cured to the arms by means of bolts or rivets H. On its inner face the plate G is grooved radially to receive cutting-tools J K, one of which may be a squaring-up tool and the other a screw-threading tool.

Each tool to be used in this machine has a screw-threaded hole in its shank to receive a bolt, L, which passes through a slot in the plate G, whereby endwise motion is permitted to the tool for the purpose of adjusting it to the size of the work it is to make, and whereby the tool may be rigidly fixed in the plate when it is set, as desired.

M is a screw in the flange D to act against the plane end of the ring E, and provided with a star feed-wheel, N, which engages a fixed spur, O, whereby the ring and its attachments are fed along upon the sleeve a little at each revolution of the ring.

P is a crank, by which the ring is revolved. Q is a leader, having a curved edge at its inner end to engage the old thread on the work, thereby guiding a threading-tool fixed to the plate to extend the old thread along the work or to clear out the old thread.

In operation it is usually necessary to turn the axle-shoulder farther back. This is done with a squaring-up tool or any other shaped point desired, using the star feed-screw. Then the leader Q and the threading-tool are set to engage the thread at different points, and the star feed-screw is removed. Now, by turning the crank, the old screw-thread may be trued out to a full thread, or the thread may be extended along the axle as far as the axle has been turned to the size of the screw. The leader Q is slotted to receive a screw-bolt, whereby it may be first set and then bound to the plate G.

What I claim as my invention, and desire to secure by Letters Patent, is—

1. The combination of the sleeve A, provided with the flange D, the radial adjusting-screws B, the ring E, provided with arms F, the radially slotted and grooved plate G, secured to the arms F, a turning-tool secur-

able to the plate, the crank P, the feed-screw M, provided with a star-wheel, N, and the spur O, substantially as shown and described.

2. The combination of the sleeve A, provided with the flange D, the radial adjusting-screws B, the ring E, provided with arms F, the radially slotted and grooved plate G, secured to the arms F, the crank P, a thread-

ing-tool fitted to plate G, and the leader Q, shaped to engage a screw-thread and slotted 10 for adjustment, substantially as shown and described.

CHARLES E. COE.
